UNITED STATES PATENT OFFICE

2,546,713

DIRT ELIMINATOR FOR POTATO SORTING MACHINES

Burr C. Baldwin, Twin Falls, Idaho

Application July 20, 1948, Serial No. 39,713

4 Claims. (Cl. 209—308)

1

This invention relates to a new and improved potato sorting machine and has for its primary object the provision of means whereby potatoes may be simultaneously screened and sorted so that dirt, stones, and rocks may be effectively eliminated in the process.

Another object of the invention is to provide a machine whereby potatoes of assorted sizes may be conveyed continuously to a sorting table in a more or less clean condition, the associated dirt and debris having been continuously removed in the interim.

Yet another object of the invention is to provide a novel means for delivering ungraded potatoes to a sorting table whereby only relatively clean potatoes will be subsequently sorted while dirt, debris, and even rocks will be effectively and continuously discharged without injury to the moving parts of the sorting machine or to the potatoes themselves.

A further object of this invention is to provide in a machine of the class described, apparatus of a simple, practical and efficient nature for effectively sorting, grading, and cleaning a variety of articles of different size.

These, together with various ancillary objects and features of the invention which will later become apparent as the following description proceeds, are attained by the device, a preferred embodiment of which has been illustrated by way of example only in the accompanying drawings, wherein:

Figure 1 is a top plan view of the device of the instant invention in operative association with an elevator and sorting table;

Figure 2 is a longitudinal sectional view taken substantially on the plane of section line 2—2 of Figure 3;

Figure 3 is a longitudinal sectional view of the device taken substantially on the plane of section line 3—3 of Figure 5;

Figure 4 is a side elevational view of the device shown in Figure 3;

Figure 5 is a vertical sectional view taken substantially on the plane of section line 5—5 of Figure 4;

Figure 6 is a fragmentary plan view of the foraminous member or screen;

Figure 7 is a sectional view taken on the plane of section line 7—7 of Figure 1; and

Figure 8 is a fragmentary longitudinal sectional view, parts being shown in elevation, of the divider element.

Specific reference is now made to the drawings. In the several views in the accompanying

2

drawings and in the following specification similar reference characters indicate corresponding elements throughout.

Generally indicated at 10 is a frame upon which is rotatably mounted an endless inclined elevator chain 12 for transporting potatoes 14 of varying sizes to a sorting table 16. The sorting table consists of a conventional conveyor 18 rotatable on sprockets 20 suitably supported on vertical standards 22.

Interposed between the elevator and the sorting table is the dirt eliminating device of the instant invention to be fully described hereinafter. A bin 24 disposed beneath the discharge end of the elevator is provided which is suitably secured to vertical frame members 26, preferably four in number. A pair of transverse shafts 28 and 30 are rotatably secured to the frame members 26. The shaft 28 is provided with a sprocket 32 over which is entrained an endless web or chain 34 which is engaged upon another sprocket 36 associated with the elevator conveyor 12. Thus shaft 28 is driven by the elevator.

Secured to shaft 28 is a substantially squared roller 38 while to the shaft 30 is secured a cylindrical roller 37.

Between longitudinal frame members 40 and supported on the rollers 38 and 37 is an endless foraminous member or screen 42 formed and configured in any desired manner but preferably as shown in Figure 6.

Positioned beneath the undersurface of the top side of the screen 42 and extending transversely thereof is an agitator which consists of a shaft 44 one end of which carries a sprocket 46 over which is entrained an endless chain 48 which engages another sprocket on the shaft 28 as shown in Figure 1. Thus the agitator is driven by the dirt eliminating conveyor. The agitator consists of a pair of spaced parallel rods 50 which are interconnected by vertical plates 52. Thus as the screen rotates on the shafts 28 and 30, the agitator is actuated to rotate whereby the rods 50 alternately abut and lift the screen a short distance to shake dirt and debris from potatoes traveling thereon as shown in Figure 3. The dirt and debris falling through the screen are deposited upon a shelf 54 to be discharged therefrom. However, small potatoes may also fall through the top side of the screen and repose on the bottom side thereof. To divide the potatoes from the dirt and subsequently discharge them on the sorting table the following means is provided.

A pair of spaced vertical lugs 56 are provided adjacent the discharge end of the screen to which

are pivotally secured as at 58 a pair of longitudinally extending arms 60. Secured to one end of the arms is a substantially V-shaped plate 62 which is disposed a definite distance above the upper surface of the bottom side of the screen 42. Thus, as small potatoes are conveyed to the right of Figure 3, on the bottom side of the screen, they will strike the plate 62 and be pushed off the screen onto the sorting table, the dirt and debris passing below the bottom edge of the plate.

The V-plate is adjustably and resiliently mounted so that a rock or hard object when striking the plate will cause it to tilt upwardly and allow the object to pass therebeneath. Terminaly secured to the free ends of the arms 60 and the lugs 56 are a pair of angularly inclined springs 62. To adjust the height of the plate 60 above the screen 42, a pair of vertical lugs 64 are provided upon the arms 60 which have internally threaded apertures to receive set screws 66 which abut the vertical lugs 56.

In practical operation, potatoes of varying sizes are lifted by the elevator to be discharged through the bin 24 onto the revolving screen 42 which is being driven by the elevator. Small potatoes, dirt and debris fall through the screen, the dirt eventually falling on the shelf 54 while the small potatoes, rocks, and other debris are moved to the right on Figure 3. The potatoes strike the sides of the V-plate, thus being pushed onto the sorting table below. The rocks and debris pass beneath the V-plate to be discharged onto the shelf 54 therebelow.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. In a potato sorting machine including an elevator and a sorting table; a dirt eliminator interposed between said elevator and said sorting table comprising a frame, a conveyor mounted on said frame, an endless foraminous member movable with said conveyor for advancing pota-

toes received thereon from the elevator, a shelf beneath the lower flight of said foraminous member and above said sorting table, means driven by said conveyor for agitating said foraminous member to loosen dirt and small potatoes therefrom and urge them through the upper flight of said foraminous member, adjustable means resiliently mounted to said frame adjacent the discharge end of said conveyor for discharging small potatoes onto said sorting table, and means below said conveyor for receiving and discharging dirt, said potato discharge means including a substantially V-shaped plate disposed transversely of said conveyor between the upper and lower flights of said foraminous member and immediately adjacent said lower flight.

2. The combination of claim 1 and a pair of longitudinally extending arms secured to the ends of said plate, means for pivoting said arms to said frame intermediate their ends, angulated springs terminally secured to said frame and to the free ends of said arms for resiliently maintaining said plate a given distance above the lower flight of said foraminous member, and means carried by said arms for adjusting the tension on said springs whereby said plate is pivoted to any desired position above the lower flight of said foraminous member.

3. The combination of claim 2 wherein said spring adjusting means includes vertical lugs on said arms having internally threaded apertures and a set screw engaging set apertures and abutting said frame.

4. The combination of claim 3 wherein said first mentioned means includes an agitator having a pair of spaced interconnected rods transversely positioned below the upper flight of said foraminous member, said rods alternately abutting and lifting the upper flight of said foraminous member as the agitator is rotated.

BURR C. BALDWIN.
